(74) Attorney, Agent, or Firm — Condo Roccia Koptiw LLP

(57) **CLAIM**

The ornamental design for a coolant expansion tank as shown and described.

DESCRIPTION

FIG. 1 is a top-front perspective view of a coolant expansion tank embodying my new design;

FIG. 2 is a top-rear perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the drawings illustrate portions of the coolant expansion tank that form no part of the claimed design.

1 Claim, 8 Drawing Sheets
